UNITED STATES PATENT OFFICE.

JOSEPH H. JONES, OF WINTHROP, AND LITFALLAH G. SABBAG, OF EAST BOSTON,
MASSACHUSETTS.

PICKER-CHECK.

1,138,660.

Specification of Letters Patent. Patented May 11, 1915.

Application filed October 7, 1914. Serial No. 865,412.

To all whom it may concern:

Be it known that we, JOSEPH H. JONES and LITFALLAH G. SABBAG, citizens of the United States, and residents, respectively, of Winthrop, county of Suffolk, and Commonwealth of Massachusetts, and of East Boston, county of Suffolk, and Commonwealth of Massachusetts, have invented an Improvement in Picker-Checks, of which the following description, in connection with the accompanying drawings, is a specification, like characters on the drawings representing like parts in each of the several views.

15 This invention relates to picker checks for looms, of the type adapted to engage the picker stick to gradually retard and stop the movement thereof while preventing any possible rebounding of the picker stick.

20 One prime object of the invention is to provide a check of this kind presenting opposite cheeks or friction engaging faces to the opposite sides of the picker stick in a manner so that the picker stick is always 25 kept central.

30 A further important object is to provide improved means whereby the friction engaging cheeks can be accurately and finely adjusted so as to present just the right amount of frictional retarding resistance to the picker stick as it approaches the limit of its movement so that rebounding of the stick on the one hand is entirely eliminated, and on the other hand the picker stick is held 35 with no more frictional resistance than necessary against its next movement.

36 In accordance with our invention a saving in regard to the shuttles is effected because it is not necessary that the binders be kept so tight and the loom can be run with less power by slackening up on the binders. Further the loom will produce better work because the filling will stay on the shuttle spindle and need not be put on so tight. By 45 reason of the fact that the picker sticks are engaged at opposite sides and held centrally by our improved device, the period of effective service thereof is lengthened, since they are kept from rubbing on the side of the 50 loom lay.

55 The foregoing and other objects and features of the invention will be better understood from the following detailed description taken in connection with the accompanying drawings and will be thereafter pointed out in the appended claims.

Referring to the drawings: Figure 1 shows in side elevation a part of one end of a loom with our invention applied thereto; and Fig. 2 is an enlarged bottom plan view of our 60 improved picker check.

The lay of an ordinary loom is indicated at 10 with the lay sword at 11 and the hand rail at 12. A usual picker stick is indicated at 13 having at its end a usual picker 14, 65 the picker stick being connected for operation in any usual or suitable way for reciprocating the picker in the shuttle box 15.

Our improved picker check indicated generally at 16 is fastened underneath the end 70 of the loom lay in position to engage the picker stick 13, it being of course understood that one of these checks will be applied at each end of the loom, though only one end is shown. In the construction of our improved 75 picker check a bracket base 17 which may have screw holes 17' for securing it to the loom lay, has at its back, upstanding ears 18 spaced apart at each side thereof, in which are threaded pins 19 having reduced inward 80 extensions 20 forming bearing supports on which the rear ends of the friction cheeks 21 are adapted to slide. Suitable keys or the like 22 are carried at the ends of the pin extensions 20 to limit the inward movement 85 of the cheek ends 21 and said cheek ends are yieldingly pressed in toward such limiting keys by springs 23 interposed between the ends of the cheeks 21 and shoulders on pins 19 formed at the point where the reduced 90 extensions 20 begin; it being noted that the springs 23 are of slightly less diameter than the pins 19. It will be noted that the pins 19 have provision to receive an implement 95 for turning the same, shown as screw kerfs 24, and are equipped with lock nuts 25. Thus by adjusting these pins in or out as required, the yielding pressure of the inner portions of the cheek pieces 21 upon the picker stick as it is embraced thereby, can be 100 varied to a nicety so that just enough friction will be exerted to bring the picker stick to a gradually retarded stop. The cheek pieces 21 are required to have a small end-wise movement and to permit this the pin 105 extensions 20 pass through elongated slots 26 in the ends of said pieces. The front ends of the cheek pieces are curved outward as seen at 27 to form a receiving guide for the entrance of the picker stick and toward the 110 front end they are formed with lateral ears or lugs 28 to which are pivoted one end of

levers 29 which are fulcrumed at 30 to posts upstanding from lateral lugs 31 on the base. The posts 30 are fitted for in and out adjustment in transverse slots 32 formed in the ears 31 and they may be clamped in adjusted position by nuts 33 set in recesses in the base. The lever members 29 extend inward beyond the fulcrums 30 as seen at 34 and they carry at their ends a coil spring 35, one end of which extends out with a bearing at 36 on the lever fulcrum, while the other end extends inward to engage with a lug 18 as seen at 37. Thus these springs exert a constant tension on the forward end of the cheek pieces tending to press them inward to full line position as seen in Fig. 2 from the dotted line position in said figure. The inner faces of the cheek pieces 21 are preferably faced with leather or other suitable friction material as indicated at 38.

In use it will be understood that as the device is mounted at each end of the lay as seen in Fig. 1, the fulcrum posts 30 will be adjusted in the transverse slots 32 and the pins 19 will be also adjusted with reference to the dimension of the picker stick to be received between the cheek pieces 21; this adjustment being such as to cause the cheek pieces to engage the picker stick and gradually retard it to a stop without on the one hand getting a stronger frictional hold on the stick than is necessary, and on the other hand catching the stick so as to prevent any possibility of rebounding thereof. It will be noted that in the movement of the cheek pieces from the full line position as seen in Fig. 2 which they occupy when the picker stick first engages therewith, to the dotted line position which they occupy after the stick has pressed them apart, there is a small forward component of motion, *i. e.*, toward the advancing stick which contributes to an effective immediate friction grip upon the stick.

We are aware that the invention may be embodied in other specific forms as to various details, for example, where coil springs are shown, such as the springs 23, these are to be understood as merely illustrative and typifying any suitable resilient or spring elements and in general it is desired that the present embodiment be considered as illustrative and not restrictive, reference being had instead to the appended claims to indicate the scope of the invention.

Having described our invention, what we claim as new and desire to secure by Letters Patent is:

1. A picker check, comprising a base adapted to be secured to the lay of a loom, a pair of cheek pieces with friction surfaces facing toward each other, presenting a picker receiving mouth, the mounting of said cheek pieces being formed to permit a yield thereof toward the back and also toward the front thereof with a component of advance toward the picker stick as it enters said mouth, and means for separately varying the extent of such yield at front and back and the normal position of the front and back portions of said cheeks respectively by separate adjustments.

2. A picker check, comprising a base adapted to be secured to the lay of a loom, and cheek pieces secured to said base presenting spaced apart friction faces to engage the sides of a picker stick, said cheek pieces having each a mounting formed to yield at the back thereof, and also to yield toward the front thereof with a swinging movement having a component of advance toward the picker stick as it enters between said pieces.

3. A picker check, comprising a base plate adapted to be secured to a lay having ears projecting out from the rear thereof, pins extending toward each other adjustably threaded in said ears, cheek pieces presenting spaced apart friction surfaces slidably fitted to said pins at their rear ends with interposed springs, said pins being formed to adjust the rear ends of said cheek pieces inward, posts mounted toward the front of said base plate adjacent each of said cheek pieces with provision for adjustment toward and from said cheek pieces, levers fulcrumed on said posts and pivotally engaged with said cheek pieces toward the front thereof, and springs for acting on said levers at the rear of said fulcrum posts and tending to press the front part of said cheeks in toward each other.

In testimony whereof, we have signed our names to this specification, in the presence of two subscribing witnesses.

JOSEPH H. JONES.
LITFALLAH G. SABBAG.
